(57) **CLAIM**

The ornamental design for a liquid dispenser, as shown and described.

DESCRIPTION

FIG. 1 is a perspective view showing our new design for a liquid dispenser, wherein the inner liquid containment portion is visible through the outer body portion, the actuator for the inner liquid containment portion is exposed within the upper end of the outer body portion;

FIG. 2 is a front elevational view of FIG. 1;

FIG. 3 is a rear elevational view of FIG. 1;

FIG. 4 is a right side elevational view of FIG. 1;

FIG. 5 is a top plan view of FIG. 1; and

FIG. 6 is a bottom plan view of FIG. 1;

FIG. 7 is a perspective view showing a second embodiment of our new design differentiated from the preceding embodiment by the orange color of the actuator, as indicated by the cross-hatching thereon;

FIG. 8 is a front elevational view of FIG. 7;

FIG. 9 is a rear elevational view of FIG. 7;

FIG. 10 is a right side elevational view of FIG. 7;

FIG. 11 is a top plan view of FIG. 7; and

FIG. 12 is a bottom plan view of FIG. 7;

FIG. 13 is a perspective view showing a third embodiment of our new design differentiated from the preceding embodiments by the color contrast of the actuator, as indicated by the stippling thereon;

FIG. 14 is a front elevational view of FIG. 13;

FIG. 15 is a rear elevational view of FIG. 13;

FIG. 16 is a right side elevational view of FIG. 13;

FIG. 17 is a top plan view of FIG. 13; and,

FIG. 18 is a bottom plan view of FIG. 13.

The broken lines are included for the purpose of illustrating a portion(s) of the liquid dispenser that forms no part of the claimed design.
